CLAIM

The ornamental design for a wear cap, as shown and described.

DESCRIPTION

FIG. 1 is a right side view of a wear cap according to the claimed design.

FIG. 2 is a bottom view of the wear cap.

FIG. 3 is a front view of the wear cap.

FIG. 4 is a top view of the wear cap.

FIG. 5 is a rear view of the wear cap.

FIG. 6 is a left side view of the wear cap.

FIG. 7 is a bottom-right perspective view of the wear cap; and,

FIG. 8 is a top-left perspective view of the wear cap mounted on a bucket tooth adapter of a bucket of an earth moving machine.

Any reflection, shadowing, or color in the drawings forms no part of the claimed design.

The broken lines in FIG. 8 of the drawings showing the bucket tooth adapter of the bucket of the earth moving machine illustrate environmental matter that forms no part of the claimed design.
